UNITED STATES PATENT OFFICE.

HARRY MATTHEWS, OF EDGEWOOD PARK, PENNSYLVANIA, ASSIGNOR TO WESTINGHOUSE ELECTRIC & MANUFACTURING COMPANY, A CORPORATION OF PENNSYLVANIA.

WINDING FOR DYNAMO-ELECTRIC MACHINES.

1,374,511.

Specification of Letters Patent. Patented Apr. 12, 1921.

Application filed September 7, 1917. Serial No. 190,099.

To all whom it may concern:

Be it known that I, HARRY MATTHEWS, a citizen of the United States, and resident of Edgewood Park, in the county of Allegheny and State of Pennsylvania, have invented a new and useful Improvement in Windings for Dynamo-Electric Machines, of which the following is a specification.

My invention relates to windings for dynamo-electric machines and it has particular relation to the so-called "squirrel-cage" windings with which the secondary members of induction motors and similar apparatus are provided.

The object of my invention is to provide means for preventing displacement of the conducting bars comprising windings of the above-described character.

In the accompanying drawings, Figure 1 is a view, partially in section and partially in end elevation, of a portion of the secondary member of an induction motor embodying my invention; Fig. 2 is a developed plan view of the parts shown in Fig. 1; parts being broken away and removed from their normal positions to show my invention more clearly and Fig. 3 is a view, similar to Fig. 1, showing a modification of my invention.

A laminated magnetizable core member 1 is provided with a plurality of partially-closed peripheral slots 2 within which are located conducting bars 3. The total cross-sectional area of each bar 3 is slightly less than that of a slot 2 and, as best shown in Fig. 2, each bar is provided with offset portions 4. The off-set portions 4 are shown in exaggerated form and are, in practice, made to project from the surface of the bar for a distance that is slightly greater than the distance A which represents the difference between the normal thickness of a bar and the width of a slot. In Fig. 3, the off-set portions 4 of the bars 3 are arranged to compensate for the difference between the radial depth of a bar and that of a slot which is represented by the distance B.

From the foregoing, it is apparent that the bars 3 may be partially inserted within the slots 2 without the application of force. However, when the off-set portion 4 of a bar engages the bottom or a side wall of a slot 2, the plane surface of the bar engages the opposite wall of the slot and it is then

necessary to apply considerable force to 55 drive the bar farther into the slot. When a bar is finally driven into position, it is very difficult to displace it because the off-set portions 4 slightly bend over the edges of the laminations comprising the core member 60 and thus tend to lock the bar in position. When all of the conducting bars have been applied to the core member, it is possible to true up the ends of the bars without danger of the bars being displaced when subsequent 65 operations are performed upon them, as, for example, in attaching end rings thereto.

While I have shown my invention in its simplest and preferred forms, it is not so limited but is susceptible of other changes 70 and modifications within the scope of the appended claims.

I claim as my invention:

1. In a dynamo-electric machine, the combination with a core member provided with 75 a plurality of longitudinally extending slots, of conducting bars located in the slots and having offset portions thereof in positive engagement with the bounding surfaces of the slots.

2. In a dynamo-electric machine, the combination with a core member provided with a plurality of longitudinally extending slots, of conducting bars located in the slots, and respectively provided with offset portions in the central portion thereof to prevent displacement of the bars within the 85 slots.

3. In a dynamo-electric machine, the combination with a core member provided with 90 a plurality of longitudinally extending slots, of conducting bars located in the slots, and provided with offset portions within said slots that are unsymmetrical with respect to the longitudinal axes of said bars. 95

4. In a dynamo-electric machine, the combination with a core member provided with a plurality of longitudinally extending slots, of conducting bars located in the slots, the said bars and the slots having different 100 cross sectional areas and each bar having an offset portion within the slots portion in engagement with the core member.

5. In a dynamo-electric machine, the combination with a core member provided with 105 a plurality of longitudinally extending slots, of conducting bars located in the slots, the said bars and the slots having different

- cross sectional areas and each bar having side-portions thereof alternately in engagement with the core member.
6. In a dynamo-electric machine, the combination with a core member provided with a plurality of longitudinally extending slots, of conducting bars located in the slots, discontinuous side portions of each bar being in engagement with the core member.
- 10 7. In a dynamo-electric machine, the combination with a core member provided with a plurality of longitudinally extending slots, of conductor bars of smaller cross-section adapted to be inserted within said slots, those portions of the bars normally within said slots being so formed as to resist longitudinal movement therein.
- 15 8. In a dynamo-electric machine, the combination with a core member provided with a plurality of longitudinally extending slots, of conducting bars of sinuous contour disposed within said slots and in engagement with the opposite walls thereof alternately.
- 20 25 9. In a dynamo-electric machine, the combination with a core member provided with a plurality of longitudinally extending slots, of conducting bars of sinuous contour and of constant cross-section disposed within said slots.
- 30 10. In a dynamo-electric machine, the combination with a core member provided with a plurality of longitudinally extending slots, of conducting bars disposed within said slots each provided with an indentation on one side thereof and with offset portions on the other side thereof, said offset portions only engaging the walls of said slot.
- 35 11. In a dynamo-electric machine, the combination with a core member provided with a plurality of longitudinally extending slots, of conducting bars disposed within said slots each provided with spaced offset portions alternately disposed on the two sides thereof, the width of said conductors at any point being less than that of the slots but the width over the ends of said offset portions being normally slightly greater than that of the slots.
- 40 45 50 In testimony whereof I have hereunto subscribed my name this 23d day of August, 1917.

HARRY MATTHEWS
